UNITED STATES PATENT OFFICE

110,656

DESIGN FOR AN ILLUMINABLE HAND MIRROR

Frederic A. Leisen, Detroit, Mich., assignor to
Oak Screw Products Company, Hillsdale,
Mich., a corporation of Michigan

Application April 12, 1938, Serial No. 76,453

Term of patent 14 years

To all whom it may concern:

Be it known that I, Frederic A. Leisen, a citizen of the United States of America, residing in Detroit, in the county of Wayne and State of Michigan, have invented a new, original, and ornamental Design for Illuminable Hand Mirror, for use as a vanity mirror and the like, of which the following is a specification, reference being had to the accompanying drawing, forming a part thereof, wherein:

Figure 1 is a front perspective view of an illuminable hand mirror embodying my new design.

Figure 2 is a rear perspective view of the mirror illustrated in Figure 1.

The dominant features of my design reside in the portions shown in full lines.

The dotted lines on the mirror face in Fig. 1 represent a small area from which the reflecting portion of the mirror has been removed to form a window portion through which light rays pass.

I claim:

The ornamental design for an illuminable hand mirror, substantially as that illustrated and described.

FREDERIC A. LEISEN.
